UNITED STATES PATENT OFFICE

91,239

DESIGN FOR A QUIN-FOCAL OPHTHALMIC LENS

Otto G. Haussmann, Philadelphia, Pa.

Application October 10, 1933. Serial No. 49,447

Term of patent 7 years

To all whom it may concern:

Be it known that I, OTTO G. HAUSSMANN, a citizen of the United States, residing at Philadelphia, in the county of Philadelphia and State of Pennsylvania, have invented a new, original, and ornamental Design for a Quin-Focal Ophthalmic Lens, as shown in the accompanying drawing and described in the following specification.

The figure is a front view of a lens showing the new design.

The lines which compose the ornamental con-

figuration on the surface of the lens in the drawing represent the boundaries of fields of different focal power in an altogether transparent medium, made visible solely by the contrast in the bending of the light rays passing through the several fields.

I claim:

The ornamental design for a quin-focal ophthalmic lens as shown and described.

OTTO G. HAUSSMANN.
